UNITED STATES PATENT OFFICE.

WILLIAM S. HELTZEN, OF LOS ANGELES COUNTY, CALIFORNIA, ASSIGNOR TO MARION G. HELTZEN, OF LOS ANGELES, CALIFORNIA.

FLUID-METER PISTON AND BEARING.

Application filed March 8, 1926. Serial No. 93,133.

This invention particularly pertains to a water meter of the type embodying a nutating piston and especially relates to the piston and the mounting therefor.

5 An object of the invention is to provide a construction in a meter of the above type whereby it will be rendered more durable and in which wearing surfaces of the piston and its bearings may be renewed without 10 necessitating renewal of the measuring chamber, as is now required in effecting replacement of excessively worn bearing surfaces in meters now generally in use and whereby worn pistons may be replaced by 15 pistons of standard sizes.

Another object is to provide a nutating piston and a mounting therefor, so formed as to be wear resistant and embodying means for effecting lubrication of the wearing 20 surface.

Another object is to provide a construction in a nutating piston whereby flushing of the bearing surfaces will be effected so as to prevent accumulation of grit on such surfaces, 25 thereby minimizing grinding and wearing away of the bearing surfaces as is ordinarily occasioned by the presence of granular particles in the fluid flowing through the meter.

A further object is to provide a nutating 30 piston which is not subject to distortion or appreciable expansion or contraction under changes of temperature.

With the foregoing objects in view, together with such other objects and advantages as may subsequently appear, the invention resides generally in the provision of a demountable bearing for a nutating piston adapted to be readily removed and replaced, and in forming the nutating piston with a 35 spherical hub having a lubricating material embodied therein, operable to effect lubrication of the bearing surface. The invention also resides in forming the piston with passages so arranged as to direct a portion of the fluid flowing through the meter to the bearing surfaces in such manner as to effect flushing thereof.

The invention further resides in the parts, in the construction, combination and arrangement of parts hereinafter described and claimed and illustrated by way of example in the accompanying drawing, in which:—

Fig. 1 is a perspective view of a nutating piston; 55

Fig. 2 is a view of a piston as seen in transverse section;

Fig. 3 is a view in cross section of a meter measuring chamber, showing a nutating piston positioned therein together with renewable 60 bearings;

Fig. 4 is a view in horizontal section as seen on the line 4—4 of Fig. 3;

Fig. 5 is a view in perspective of the upper bearing member with portions broken away; 65

Fig. 6 is a perspective view of the lower bearing member with portions broken away.

Fig. 7 is a plan view of the spherical hub;

Fig. 8 is a detail in cross section of the hub as seen on the line 8—8 of Fig. 7 showing 70 the lubricating element.

Referring to the drawings more specifically, 10 indicates a nutating piston which embodies a circular disk 11 provided at its center with a spherical hub 12; the disk projecting diametrically of the hub as is common in pistons of this character. The disk is here shown as flat, but may be of any suitable configuration. The hub 12 is here shown as formed in two pieces, each of 75 which is in the shape of a segment of a sphere and provided with an opening 13 formed in the hub; the two halves of the sphere being positioned on opposite sides of the disk and connected together by a screw 14 having a head 15 countersunk in a recess 16 formed in the lowermost sphere section, and which screw extends through the sphere and is formed with an end extension or stem 17 for actuating the usual registering mechanism, not necessary to be here shown. The hub and disk may, however, be formed integral but are preferably separable as here shown so as to permit renewal of the hub should occasion require, without necessitating renewal of the disk. 80 85 90 95

The nutating piston is arranged in a measuring chamber 18 which embodies upper and lower members 19 and 20 forming an annular passage 21 extending around the spherical hub and across which the disk 11 extends. 100

A partition 22 extends transversely across the passage 21 from the periphery of the spherical hub through an opening in the side wall of the passage which opening constitutes a fluid inlet 23 on one side of the parti- 105

tion 22 and a fluid outlet 24 on the opposite side thereof; the disk 11 being formed with a slot 25 into which the partition 22 extends as is common in fluid meters of this character.

The bottom wall of the passage 21 is formed by an upwardly projecting frustoconical wall 26 of the housing member 20 and the upper wall of the passage 21 is formed by a downwardly projecting frustoconical wall 27 of the housing member 19.

An important feature of the present invention resides in providing the apex portions of the walls 26 and 27 with demountable socket bearings 28 and 29 respectively, in which the spherical hub of the piston seats and is supported for nutating movement. The lower bearing 28 comprises a cylindrical portion 30 having an outwardly projecting 20 marginal flange 31 on its upper end, which cylindrical portion is adapted to be inserted in an opening 32 formed in the bottom wall 26 with the flange 31 seating on the margin of said opening.

The upper face of the flange 31 is beveled so as to extend on an inclination corresponding to and in continuation of the inclined upper surface of the wall 26.

The upper bearing member 29 embodies an annulus 33 formed with a marginal flange 34 which annulus is inserted in an opening 35 in the wall 27 with the flange 34 seating on the margin of the opening. The outer face of the flange 34 is beveled and extends in continuation of the inclined inner surface of the wall 27. The body portions of the bearing members 28 and 29 are preferably formed of a composition, such as bakelite, and have their socket portions which receive 40 peripheral portions of a sphere lined with facings 36 and 37, respectively, formed of metal; the facing 36 in the lower socket member 28 being in the form of a segment of a sphere while the facing member 37 in the bearing 29 is annular and has its outer surface concave and conformable to the peripheral surface of the spherical bearing. The metallic facings 36 and 37 are embedded in the composition forming the body portions 50 of the bearings.

The bearing members slidably fit the openings in the walls 27 and 28, which permits their ready removal and replacement.

Another important feature of this invention resides in forming the spherical bearings with a pair of passages 38 and 39 which lead diagonally through the spherical hub as particularly shown in Figs. 2 and 7, the lower end of the passage 38 opening adjacent the underside of the disk 11 and the upper end thereto opening adjacent the stem 17 at a point where on imparting nutative movement to the spherical hub it will be

presented to the bearing surface of the upper bearing 29 so that when the disk is inclined, as shown in Fig. 3, to position the lower end of the passage 38 in communication with the annular passage 21, fluid entering the latter through the opening 23 will be directed through the passage 38 against the bearing surface and thereby effect a flushing action thereon. The upper end of the passage 39 opens adjacent the upper face of the disk 11 and its lower end is presented to the bearing surface of the lower bearing member on the nutative movement of the hub member so that when the disk is disposed at an inclination opposite that shown in Fig. 3, a portion of the fluid entering the passage 21 through the inlet 23 above the disk will be directed through the passage 39 against the bearing surface of the lower bearing 36 and thereby effect a flushing action thereon.

Another important feature of the present invention resides in forming the spherical hub with a self-lubricating surface which is here shown as accomplished by placing a series of plugs 40 in recesses 41 formed at appropriate points throughout the surface of the spherical hub, as particularly shown in Fig. 8; the plug 40 being preferably formed of lignum vitae, which material is especially desirable because of its extreme hardness and its oil constituent.

I claim:

1. In a meter of the character described, a measuring chamber having top and bottom walls, a socket bearing in the bottom wall, an annular bearing in the top wall, a nutating piston arranged in said chamber including a spherical hub seating in said bearings, said hub being formed with passages leading from the measuring chamber to the surfaces of said bearings.

2. In a meter of the character described, the combination of a measuring chamber, a nutating piston therein including a spherical hub having recesses, bearings for said hub demountably supported in said chamber, and a series of lignum vitae plugs carried in the recesses of said hub arranged to afford lubrication and wear resisting qualities of the bearing surfaces between the hub and bearings.

3. In a meter of the character described, a measuring chamber having top and bottom walls, a socket bearing in the bottom wall, an annular bearing in the top wall, a nutating piston arranged in said chamber including a spherical hub seating in said bearings, said hub being formed with straight cylindrical passages leading from the measuring chamber to the surfaces of said bearings.

In testimony whereof I have affixed my signature.

WILLIAM S. HELTZEN.
